ENGINE STARTER GEARING FOR INTERNAL-
COMBUSTION ENGINESBurr W. Jones, Elmira, N. Y., assignor to Béndix
Aviation Corporation, South Bend, Ind., a cor-
poration of Delaware

Application April 21, 1943, Serial No. 483,954

6 Claims. (Cl. 74—6)

The present invention relates to starter gearing for internal combustion engines and more particularly to that type of gearing in which a motor driven pinion is shifted axially into engagement with an engine gear prior to energization of the starting motor, the pinion being arranged to overrun the starting motor when the engine starts.

In devices of this type as now commercially manufactured, it is usual to incorporate special provisions for enforcing proper mesh of the pinion in case of tooth abutment. Moreover, the forms of overrunning clutch generally used tend to generate quite severe localized stresses which necessitate a comparatively heavy and expensive structure and which may cause the clutch to jam and fail to release.

It is an object of the present invention to provide a novel starter gear shift which is efficient and reliable in operation and simple and economical in construction.

It is another object to provide such a device in which a single element of elastically deformable material is used both as a mesh enforcing means for the starting pinion and as an overrunning clutch member for rotating the pinion.

It is another object to provide such a device in which jamming or sticking of the clutch is effectively prevented.

It is another object to provide such a device in which a small portion of the elastic element is used to cushion the meshing operation, while the entire element is used to transmit torque to the pinion to crank the engine.

Further objects and advantages will be apparent from the following description taken in connection with the accompanying drawing in which:

Fig. 1 is a side elevation partly in section of a preferred embodiment of the invention;

Fig. 2 is a similar view showing the parts in the positions assumed when a tooth of the pinion abuts against the tooth of the engine gear;

Fig. 3 is a view similar to Fig. 1 showing the parts in cranking position;

Fig. 4 is a detail of the driving and shifting barrel member partly broken away to show the clutch actuating cam means;

Fig. 5 is a detail in perspective of the yielding clutch member; and

Fig. 6 is a detail in perspective of the centering and supporting element for the yielding clutch member.

In Fig. 1 of the drawing, there is illustrated a power shaft 1 which may be the extended armature shaft of a starting motor not illustrated.

A portion 2 of the power shaft is formed with splines or key-ways on which is slidably but non-rotatably mounted the hub 3 of a barrel member 4. The hub 3 is formed as a grooved shift collar and means such as a fork member 5 controlled by the operator is provided for sliding the barrel axially along the power shaft 1.

A pinion 6 is slidably journaled on the power shaft 1 for movement into and out of engagement with a member such as a gear 7 of an engine to be started. The pinion is arranged to telescope within the barrel 4 and a flange member 8 having a splined connection at 9 with the teeth of the pinion, is retained in the end of the barrel by means of an annular plate member 11 keyed to the barrel at 12 and retained by a lock ring 13. A stop ring 14 is rigidly fixed to the end of the pinion 6 and limits the projection of the pinion from the barrel by abutting against the interior of the flange member 8.

Means forming an overrunning clutch connection between the barrel and the flange member 8 is provided in the form of an annular block 15 of elastically deformable material such as rubber mounted in the barrel member adjacent the flange member. The inner end of the barrel is provided with cam members 16 (Fig. 4) and the adjacent surface of the rubber block 15 has preferably molded thereon a driven cam member 17 arranged to cooperate with the cams 16 to compress said block against the flange member 8 when torque is transmitted from the barrel to the block.

According to the present invention a portion 35 of the yielding clutch member 15 is used to normally maintain the pinion 6 in extended position with respect to the barrel 4 as illustrated in Fig. 1 but to yield and permit the pinion to telescope into the barrel in case of tooth abutment with the engine gear as shown in Fig. 2. This is accomplished by extending a portion of the member 15 radially inward as shown at 18 and forming a groove 19 back of said shoulder so as to make that portion of the block comparatively elastic. The portion 18 of the rubber block is arranged to bear against the stop ring 14 on the pinion and thus normally hold the ring against the inner surface of the flange member 8.

50 In order to reduce the friction between the periphery of the clutch block 15 and the inner surface of the barrel 4, it is preferable to provide a sleeve 21 surrounding said block to prevent its radial expansion and provide a free bearing in the barrel. Means for centering the block

15 and providing a bearing therefor on the power shaft may also be provided as illustrated in Fig. 6 wherein is shown a bearing ring 22 journaled on the splined portion 2 of the power shaft and supporting the interior of the block and the driven cam member 17. The member 22 may, if desired, be provided with radially extending projections 23 which cooperate with the driven cam member 17 to lock the elements for rotation in unison.

In operation, starting with the parts in the positions illustrated in Fig. 1, actuation of the shift fork by the operator to move the barrel along the power shaft causes the pinion 6 to mesh with the engine gear 7 as shown in Fig. 3. At this time the starting motor is actuated by suitable means to cause rotation of the power shaft in the direction of the arrow which rotation is transmitted through the splined connection to the barrel. The cams 16 thereupon compress the clutch block 15 against the flange member 8 which is thus clutched to the barrel by its frictional engagement with the block 15 on one side and the disc 11 on the other. The tightening of the clutch so formed proceeds until rotation is transmitted through the flange 8 to the pinion 6 to rotate the engine gear 7 and crank the engine. When the engine starts, the acceleration of the engine gear causes the pinion 6 to overrun, thus releasing the clutch members, whereupon the parts are returned to their positions by the operator.

If, during the meshing operation, a tooth of the pinion should abut against the engine gear, the longitudinal movement of the pinion is stopped but the shifting of the barrel member continues as permitted by the deformation of the portion 18 of the clutch block. When the barrel has been shifted into starting position and the starting motor energized, torque is transmitted through the self-tightening clutch 15, 8, 11 to the pinion to index it into proper registry with the tooth spaces of the engine gear, whereupon the portion 18 of the yielding member 15 snaps the pinion into mesh with the engine gear and cranking proceeds in the usual manner.

Although but one embodiment of the invention has been shown and described in detail, it will be understood that other embodiments are possible and various changes may be made in the construction and arrangement of the parts without departing from the spirit of the invention as defined in the claims appended hereto.

What is claimed is:

1. In an engine starter, a power shaft, a pinion slidably journaled thereon, and means having a splined connection with the pinion transmitting torque from the shaft to the pinion, said means including a member of elastically deformable material, a portion of said member bearing on the pinion to yieldingly transmit longitudinal movement thereto.

10 2. In an engine starter, a power shaft, a barrel member splined thereon, a pinion having a limited telescopic movement in the barrel and an overrunning clutch connection between the barrel and pinion including a yielding member, said yielding member cooperating with the pinion to normally hold it in extended position with relation to the barrel.

15 3. In an engine starter, a power shaft, a barrel member splined thereon, a pinion having a limited telescopic movement in the barrel, a friction 20 clutch connection between the barrel and pinion, and torque responsive means for tightening the clutch including a yielding member a portion of said yielding member engaging the pinion to resist telescopic movement thereof.

25 4. In an engine starter, a power shaft, a barrel member splined thereon, a pinion slidably journaled on the shaft, a flange member in the barrel splined to the pinion, means including an annular block of elastically deformable material 30 in the barrel providing a one-way driving connection from the barrel to the flange member, said block having a portion engaging the pinion to yieldably transmit longitudinal movement from the barrel to the pinion and means for traversing 35 the barrel on the shaft to move the pinion into and out of engagement with a member of an engine to be started.

5. An engine starter gear as set forth in claim 4, including further means for confining and 40 supporting the block of elastically deformable material to prevent its bearing frictionally in the barrel.

45 6. In an engine starter, a power shaft, a barrel member splined thereon having cam means therein, a pinion slidably journaled on the shaft, a flange member in the barrel splined to the pinion, and an annular block of elastically deformable material in the barrel cooperating with 50 said cam means to provide a one-way driving connection from the barrel to the flange member, said block having a small portion engaging the pinion to yieldably transmit longitudinal movement from the barrel to the pinion.
